DUPLICATOR

Theodore Danheiser, New York, N. Y., assignor
to The Beck Duplicator Company, a corpora-
tion of New York

Application March 13, 1935, Serial No. 10,784

8 Claims. (Cl. 101—132)

The invention relates to duplicators, of that form in which a negative or reversed impression of matter to be copied is made upon a duplicating surface and positive impressions taken therefrom by bringing sheets of paper or the like in contact therewith, and it more particularly relates to that form of duplicator in which the duplicating surface is mounted upon a rotating member.

One of the principal objects of the invention is to provide simple, efficient, economical and adaptable means whereby the rapid handling of sheets of paper and the feeding of the same to the duplicating surface either automatically or by hand as may be desired and the positioning of the same with relation thereto, are facilitated. Further objects and advantages of the invention will be in part set forth in the following specification and in part will be obvious therefrom without being specifically pointed out, the same being realized and attained as hereinafter more fully described or as set forth or pointed out in the claims hereof.

With the above and other objects of the invention in view, the invention consists in the novel construction, arrangement and combination of various devices, elements and parts, as set forth in the claims, hereof, certain embodiments of the same being illustrated in the accompanying drawings and described in this specification.

In the accompanying drawings,

Fig. 1 is a perspective view of a duplicator, showing one embodiment of my invention, as the same appears when used for the automatic or mechanical feeding of sheets of paper to the duplicating surface;

Fig. 2 is a perspective view, partly broken away, showing the same type of duplicator, arranged for hand-feeding of paper; and

Fig. 3 is a fragmentary view, on a somewhat reduced scale, showing a modified form of the mechanism.

In carrying my invention into effect in one of the embodiments selected for illustration in the accompanying drawings and for description in this specification, and referring now to Figs. 1 and 2 of the drawings, it will be seen that I provide a main frame structure, which may be of any form suitable for the purpose. As shown, the same comprises side members 17, secured together so as to form a frame of sufficiently rigid construction, which frame supports various moving and other parts of the machine.

Supported by the side frame members 17 is the

main rotating member which principally performs the actual duplicating work. It will be seen that this comprises a gear-wheel 19 and a plain wheel 20, of approximately the same size, connected by the semi-cylindrical sheet-metal bed 21. The latter may if desired be padded with fabric or other soft material, in the usual manner.

This rotary frame carries the adhesive duplicating surface used in the machine. The latter is not shown in the drawings, and may be applied to and assembled with the machine in any suitable manner. It may if desired consist of a film sheet, provided with suitable attaching means, such as metal ends having hooks or clamps to hold the sheet in place upon the bed, or it may if desired consist of a sheet or roll of substantial length, the ends of which are secured to spindles upon and from which the same may be wound and unwound and upon one or both of which the portions not in use may be stored. The spindles may be mounted in the rotary frame in any suitable manner, as for instance by means of the devices shown at 51. It will be seen that these devices in no way interfere with the work being done on the machine when a sheet is used, and that the machine is therefore equally well adapted for either a sheet or a roll.

It will be understood that suitable means for operating the machine are provided, which do not show in the drawings, as the same would be hidden by the wheel 19, and since the particular means for rotating the rotary frame form no part of the present invention it is not thought necessary to illustrate the same. The same would preferably consist, in a machine of the type and size illustrated, of a crank connected with the main shaft 31 and adapted to be turned by hand, but electric or other driving means may be used if preferred.

The wheel 19 is shown in the drawings as a gear wheel, but this characteristic forms no essential part of the present invention, the gearing being intended for cooperation with other mechanism not shown in the drawings, as for instance striping mechanism as shown in Letters Patent No. 1,949,154 or Letters Patent No. 1,974,266, or, if desired, driving mechanism as shown in the latter patent.

Extending forwardly from the side frame members 17, are shoulders or extensions 24, having inclined upper surfaces or edges, each of which has a fixed pin or stud 36. Between these shoulders is mounted a substantially horizontal table 25, adapted to support a pile of paper from which individual sheets are mechanically or automatic-

cally fed to the duplicating surface. The feeding mechanism as shown comprises an arm 60, loosely mounted on the shaft 61, and provided with a rubber roll 62. The shaft 61 is mounted in arms 63, which are pivotally secured in the sides of the table 25, and are reciprocated by means of the arm 65, when the mechanism is arranged as shown in Fig. 1. This arm 65 is provided with a hook 67, which engages the crank 69 on the rotary frame when it is desired that the automatic feeding means shall operate, and which may be disengaged therefrom (see Fig. 2) and engaged with the stud 68, or held out of the way in any other convenient manner, when it is desired that the automatic feeding means shall be inoperative.

It will be understood that by this means the reciprocating of the feeding mechanism, as the rotary frame is operated, will cause the arm 60 to push one sheet of paper toward the duplicating surface upon each rotation thereof, if the arm 65 is operatively engaged with the crank 69.

Adjustable paper-guides 26, 27, 28, and 29 are provided, also a guide 71, under which the paper passes in reaching the duplicating surface, and which insures against curling up or other displacement of the advancing edge of the duplicating surface. A locating mark 70 is also provided, to show the correct position for the edge 30 of the pile of sheets.

Just behind the table 25 is a roller 32, and behind said roller is a stop 35. The relative adjustment of the parts is such that a sheet of paper fed by the arm 60 will come to rest with its advancing edge over the roller 32, and will be prevented from going too far by means of the stop 35. This stop is so mounted that as the rotary frame is turned, the stop 35 will be depressed out of the way of the advancing duplicating surface, 40 allowing the paper to be carried around thereby, and the roller 32 is also movably mounted so as to co-operate in bringing the paper into contact with the duplicating surface and thereafter to act as an impression roller. The particular 45 means for mounting and operating this roller and stop form no essential part of the present invention, and the same may be as shown in Letters Patent No. 1,949,154 or 1,974,266 above mentioned, or of any other suitable or desired type.

50 A removable inclined paper-shelf 50 is provided, adapted to be supported upon the shoulders 24 between which the table 25 is mounted. This shelf 50 has downturned edges 51, slots 52 and 53, and adjustable paper-guides 54. The slots 52 engage with the pins 36, and the larger notches 53 are adapted to clear the wheels 19 and 20, thereby permitting the shelf 50 to be mounted close to the roller 32. Slots 58 are provided for the attachment if desired of an additional horizontal paper-supporting table, to hold a pile of sheets from which single sheets may be fed down by hand upon the inclined shelf 50.

It is thought that the operation of this embodiment of the invention will be clear from what 65 has been said, but the same may be briefly recapitulated as follows: The first step is the impression upon the duplicating surface of a reversed or negative impression of the material to be copied, this being derived from the usual master-sheet, which is written, printed or otherwise prepared in suitable duplicating ink. This master copy may be applied to the duplicating surface in either of the ways about to be described with reference to the blank sheets of

paper, and may afterwards be stripped either by hand or by any suitable means, not shown.

If the matter impressed upon the duplicating surface is a letter, sketch, or other matter in which very accurate position of the copies on the successive sheets of paper is not especially essential, the table 50 is lifted off, and the arm 65 engaged with the crank 69, as shown in Fig. 1.

A pile of sheets of blank paper is then placed upon the table 25, the roll 62 resting upon the top sheet. The adjustable guides are adjusted so that the paper will feed in a straight direction, and, upon the rotary frame being turned, by hand or otherwise, successive sheets will be fed to the duplicating surface, with convenience, 15 speed, and sufficient accuracy of positioning for all ordinary purposes. That is to say, the forward or backward variation in position of successive sheets fed in this manner will amount to a fraction of an inch, and would not be at all 20 objectionable in the case of a letter or similar work.

When it is desired to make copies upon printed blanks or in other cases where perhaps even a sixteenth of an inch or less would spoil the appearance of the finished work, or even result in illegibility or inaccuracy on account of the misplacement of the matter in duplicating ink with reference to matter already on the page, and where correct positioning is therefore preferred 30 to extreme speed and convenience, the shelf 50 is replaced, the arm 65 disconnected from the rotary frame, and the sheets of paper are then fed by hand, one at a time, down the shelf 50. In such case the paper passes down by gravity 35 until it comes to rest against the stop 35, and is accurately positioned thereby and held in place until the duplicating surface picks it up and carries it around, the stop at the same time being depressed out of the way as already explained. 40

A modified form of the positioning means for the pile of paper is shown in Fig. 3 of the drawings. In this form of the invention, most of the parts are similar to those already described, and it is not believed necessary to refer 45 to the same in detail. Instead of providing indicating means as shown at 70 in Fig. 1, however, I provide in this embodiment a movable stop 175. The table 125 is cut away to the point at which the edge of the pile should be 50 placed, and the stop 175 stands vertically at this point. When it is desired to operate the machine, the stop 175 is turned out of the path of the paper by rotating the knob 179 and shaft 181, in a clockwise direction. This knob is slidably mounted at the end of the shaft, having an internal spring (not shown) which tends to hold the knob closely in against the side portion 182 of the table 125. A pin 180 may engage a perforation in the portion 182 in the position shown 60 in the drawings, or, when the knob and shaft are slightly rotated, may engage a second perforation (not shown because hidden by knob 179), thereby holding the shaft 181 in either of two positions and permitting no intermediate position thereof. The stop 175 is operatively connected with the shaft 181 by members 176, 177, and 178, in a manner which will be obvious from said Fig. 3.

The operation of the invention is in other 70 respects entirely similar to the operation of the first-described embodiment of the invention.

The advantages of the invention will be in large part self-evident. The combination feed above referred to will feed either automatically 75

or by hand, and where there is a variety of duplicating work to be done, involving various size forms or requiring perfect registration, this combination-feed machine will take care of such requirements, with the utmost in speed and convenience. The simple hand feed attachment may be placed in position in a few seconds, and the automatic feed disconnected, or vice versa. In this way the machine is applicable for all kinds of forms as well as work on plain paper, letterheads, &c., without the necessity of separate machines, or of any elaborate fixtures, small parts which may become lost, set-screws or other devices which must be inserted or removed. It will also be seen that in addition to the simplicity with which the combination-feed may be adjusted for either type of operation, all parts are equally conveniently located in either case; no tools are necessary in changing the feed, nor is any special skill required. In actual use the invention has proved to be a saving in expense as well as an increase in usefulness, in offices having the type of work referred to. Other advantages of the invention will also be obvious to any one familiar with such devices, and will be evident from what has been above said and from the drawings.

I do not limit myself to the particular details of construction set forth in the foregoing specification and illustrated in the accompanying drawings, as the same refer to and set forth only certain embodiments of the invention, and it is obvious that the same may be modified, within the scope of the claims hereof, without departing from the spirit and scope of the invention.

It is obvious, for instance, that my combination feeding mechanism may be used with any suitable type of rotary frame and appurtenant parts; also that if desired a removable set-screw, a spring latch, or any other suitable device, may be used instead of the hook 67, for conveniently connecting and disconnecting the arm 65 with the rotary frame; other minor variations also will occur to those skilled in this art.

Having thus described my invention, what I claim as new and desire to secure by Letters Patent, is as follows:

1. In a duplicator, the combination with a stationary frame and a rotary frame adapted to support a duplicating surface; of means adapted to bring paper into contact with said duplicating surface in a predetermined position either automatically or by hand as may be desired, said means comprising a substantially horizontal paper-supporting shelf or table, an inclined paper-supporting shelf or table adapted to be removably mounted over said first-named shelf or table, and automatic means adapted to feed paper on said horizontal shelf or table toward said rotary frame, said automatic means being detachably operatively connected with said rotary frame, said lower shelf or table being provided with means adapted to support said upper shelf or table when the latter is in use, whereby when it is desired to feed paper automatically to said duplicating surface said automatic feeding device may be connected with said rotary frame and operated thereby and said inclined shelf removed, and when it is desired to feed paper by hand to said duplicating surface said inclined shelf may be placed in position and said automatic feeding device disconnected from said rotary frame and placed in non-operative posi-

tion without substantial change of location relatively to the machine as a whole.

2. In a duplicator, the combination with a stationary frame and a rotary frame adapted to support a duplicating surface; of means adapted to bring paper into contact with said duplicating surface in a predetermined position either automatically or by hand as may be desired, said means comprising a paper-supporting shelf or table, a second paper-supporting shelf or table adapted to be removably mounted over said first-named shelf or table, said lower shelf or table being provided with means adapted to support said upper shelf or table when the latter is in use, and automatic means adapted to be operated by said rotary frame and to feed paper on one said shelf or table toward said rotary frame.

3. In a duplicator, the combination with a stationary frame and a rotary frame adapted to support a duplicating surface; of means adapted to bring paper into contact with said duplicating surface either automatically or by hand as may be desired, said means comprising a substantially horizontal paper-supporting shelf or table, an inclined paper-supporting shelf or table adapted to be removably mounted over said first-named shelf or table, said lower shelf or table being provided with means adapted to support said upper shelf or table when the latter is in use, automatic means on one first-named shelf or table adapted to feed paper toward said rotary frame, said automatic means being detachably operatively connected with said rotary frame, and a stop or guide against which an edge of a sheet of paper may abut and be brought to rest thereby in the path of said duplicating surface.

4. In a duplicator, the combination with a stationary frame and a rotary frame adapted to support a duplicating surface; of means adapted to bring paper into contact with said duplicating surface either automatically or by hand as may be desired, said means comprising a substantially horizontal paper-supporting shelf or table, an inclined paper-supporting shelf or table adapted to be removably mounted over said first-named shelf or table, said lower shelf or table being provided with means adapted to support said upper shelf or table when the latter is in use, automatic means adapted to feed paper on one said shelf or table toward said rotary frame when desired and to be placed in inoperative position when desired without substantial change of location relatively to the machine as a whole, a movably mounted stop or guide against which an edge of a sheet of paper may abut and be brought to rest thereby in the path of the duplicating surface, and means adapted to move said stop out of the path of said duplicating surface at a predetermined point in the operation of the machine and thereby release said paper in the path of the duplicating surface as the same approaches said paper.

5. In a duplicator, the combination with a stationary frame and a rotary frame adapted to support a duplicating surface; of means adapted to bring paper into contact with said surface either automatically or by hand as may be desired, comprising a paper-supporting shelf or table, automatic means adapted to feed paper thereon toward said rotary frame, a second shelf or table adapted to be removably mounted over said first-named shelf or table for hand feeding of paper toward said rotary frame, said lower shelf or table being provided with means adapted to sup-

port said upper shelf or table when the latter is in use.

6. A combination as set forth in claim 5, in which said upper shelf or table is supported in such position that said automatic means need not be removed from the normal location thereof relatively to the machine as a whole.

7. In a duplicator, the combination with a stationary frame and a rotary frame adapted to support a duplicating surface; of means adapted to bring paper into contact with said surface either automatically or by hand as may be desired, comprising a paper-supporting shelf or table, automatic means adapted to feed paper thereon toward said rotary frame, a second shelf or table adapted to be removably mounted in position for hand feeding of paper toward said rotary frame, said lower shelf or table being provided with inclined shoulders and

fixed engaging means adapted to support said upper table when the latter is in use.

8. In a duplicator, the combination with a stationary frame and a rotary frame adapted to support a duplicating surface; of means adapted to bring paper into contact with said surface either automatically or by hand as may be desired, comprising a paper-supporting shelf or table, automatic means adapted to feed paper thereon toward said rotary frame, a second shelf or table adapted to be removably mounted in position for hand feeding of paper toward said rotary frame, said first-named shelf or table being provided with means adapted to support said second-named shelf or table when the latter is in use, in such position that said automatic means need not be moved from the normal location thereof with relation to the machine as a whole.

THEODORE DANHEISER.
